(57) **CLAIM**

I claim the ornamental design for an auxiliary handle for a shovel, as shown and described.

DESCRIPTION

FIG. 1 is a perspective view of the auxiliary handle for a shovel,

FIG. 2 is a front end view of the auxiliary handle,

FIG. 3 is a rear end view of the auxiliary handle,

FIG. 4 is a top view of the auxiliary handle,

FIG. 5 is a bottom view of the auxiliary handle,

FIG. 6 is a left hand side view of the auxiliary handle; and,

FIG. 7 is a right hand side view of the auxiliary handle.
